UNITED STATES PATENT OFFICE

WILLIAM M. BOUDION, OF NEW YORK, N. Y.

CIRCUIT BREAKER

Application filed May 6, 1929. Serial No. 360,962.

My invention relates to protective devices for use with vapor or gas electric devices, wherein a discharge takes place through a rarefied atmosphere of a suitable gaseous material, such as a neon lamp or the like.

Such devices which have come into general use for advertising signs and the like are usually energized by a high tension alternating current obtained from a specially constructed transformer. The characteristics of this transformer are such that if the circuit of the output side is interrupted for any reason an excessive potential is developed by the transformer, which may lead to destruction of the apparatus connected thereto, or the transformer itself, if it be allowed to continue for any great length of time.

Protection against this danger can not be obtained by the expedient which is successful in other electrical contrivances, namely, the providing of a fuse or circuit breaker so arranged that upon passage of an excessive circuit, the fuse will be melted and the circuit thus interrupted, because this excessive potential will be developed without necessarily producing any great load in the primary circuit, in fact, the primary current will probably be decreased instead of increased, so that a fuse of the ordinary type would provide no protection whatever.

Such high potentials are developed when, for instance, one of the units of a neon sign is broken in any way, or if for any reason the discharge of electricity therethrough be interrupted and not immediately re-established.

The principle upon which my invention is based is that a spark gap is connected to the terminals of the high tension winding of the transformer, the terminals of said gap being spaced so far apart that in the normal operation of the device a discharge will not take place between said terminals, however, upon the occurrence of an abnormal high potential such discharge will result and actuate the protective means. This protective means comprises a fuse wire of the ordinary type or even a non-conducting element, which is arranged so that the primary circuit is interrupted when the said protective element is

severed in any way, and this severing takes place due to the heat of the spark or arc produced between said spark gap terminals, when the potential is abnormal.

The distinction between a device of this type and the ordinary fuse is that the severing of the fuse or its equivalent is produced, not by the heat developed by the current passing through said element itself, but by the heat of a discharge produced independently in the secondary circuit of the transformer.

For a description of my invention and a fuller understanding of the above and other objects thereof, attention is directed to the accompanying drawings, wherein several embodiments of the invention are illustrated by way of example.

In said drawings:

Figures 1 and 2 illustrate one embodiment of the device with parts thereof in different positions.

Figure 3 is a central longitudinal section of the device of Figures 1 and 2.

Figure 3^a is a diagrammatic view illustrating the application of the device.

Figures 4, 5 and 6 illustrate the front, rear and side view respectively of a second embodiment of the invention.

Figures 7 and 8 are similar views of a third embodiment of the invention.

Referring now specifically to Figure 1, there is shown a base 16 made of any desired suitable insulating material, preferably such as glass, porcelain, phenol-resin and the like, having a cover 17 of similar material fitted thereto, as shown.

Within the casing 16 is provided the primary circuit which is indicated diagrammatically, starting at the wire 18, coming from one of the lines feeding the primary circuit, passing to the terminal 2, thence through a resilient element 3 having a contact 4 at its end to a cooperating contact 5, held at the end of a resilient element 6, in turn connected to a terminal 7.

A test lever 1 arranged pivotally at 19 may be actuated to bring the elements 4 and 5 into contact with one another when in the position shown in Figure 1. From the bind-

ing post 8 at the end of the terminal 7, a length of fusible wire 11 leads to the binding screw 12 of the terminal 13, also arranged in the casing, as shown. A wire 20 leads from terminal 13 to one terminal of the primary winding of the transformer, not shown. Two additional terminals 9 and 10, respectively, are connected to the two terminals 21 and 22 of the secondary winding of said transformer. These terminals 9 and 10, which are pointed, as shown, are adjusted to such spacing from one another that in the normal operation of the transformer the potential thereof is insufficient to jump the gap from one to the other, or from either to the interposed fuse wire 11.

In operation, it is obvious that when the potential of the secondary increases sufficiently, a spark or arc will form between the terminals 9 and 10, or between one of them and the fuse wire 11, and the heat produced thereby will suffice to melt the wire 11, and thus interrupt the primary circuit of the transformer.

In the form shown in Figure 2, the arrangement is substantially the same as that of Figure 1, and the apparatus is, in fact, identical with the exception that it is here arranged to use a non-conducting element 14 as the protective means, instead of the metallic wire 11 of Figure 1. This non-conductive element 14, which may be a combustible element, such as a twisted strip of paper, a thread, a piece of string or cord or the like, or merely a fusible element such as a thin rod of glass, is secured at one end to the screw 12, and at the other end to a hook 15 on the resilient element 3. This non-conductive element 14 passes freely over or around the binding post 8 and, of course, takes no part in the conduction of the current.

When the element 14 is inserted, it is arranged with sufficient tension to bring the contact members 4 and 5 into electrical contact with one another, as shown in Fig. 2, and when the device is used in this manner the lever 1 is turned about its pivot 19, so that it is out of contact with the resilient element 3, which is then held merely by the element 14. In this manner of using the device, the primary terminal 20 of the transformer which was formerly connected to terminal 13 is now connected instead to binding post 7, as shown, and terminal 13 is not used electrically. Here the operation is the same as that of Figure 1, insofar as the occurrence of an arc or spark between the terminals 9 and 10 results in destroying the element 14, by melting it or by setting it on fire, or otherwise disrupting it, whereupon the resilient spring 3 is freed and withdraws the contact 4 from the contact 5, thus again interrupting the primary circuit of the transformer.

A modified form of the device, which is

considered at present the preferred form, is shown in Figures 4, 5 and 6, and comprises a casing 23 which is of a generally cylindrical shape, which may be of any suitable insulating material.

This casing is provided with a cover 24, which may be retained in place by means of a resilient metallic element 25 pivoted at 26 to the said casing 23. The said casing contains two studs 27 and 28, having binding screws 29 and 30 thereon, between which a piece of fuse wire 31 may be connected, as shown.

The spark terminals of the secondary circuit are here indicated by 32 and 33, and are carried upon the bent ends of slidable elements 34 and 35 which are located so that the spark gap is arranged at approximately right angles to the fuse wire, as shown. These slidable elements 34 and 35 may be secured in their adjusted position in any desired way, forming no part of the invention itself. The operation of this form is obvious from what has been stated regarding the diagrammatic Figures 1 and 2, and briefly consists in adjusting the spark gap between terminals 32 and 33 as before, so that a discharge does not pass between them until the voltage of the secondary becomes excessive, whereupon such discharge will again serve to melt the fuse wire 31 and thus interrupt the primary circuit.

The form of the invention shown in Figures 7 and 8 comprises a base of insulating material 36 which carries thereon the terminals 37 and 38, between which the fuse wire 40 is connected, as in the other forms, additional lugs 41, 42 being provided to support said wire centrally in position, as shown. Each of these lugs 41 and 42 has a centrally placed notch 43 therein for this purpose. The terminal 38 is connected electrically to the terminal 39 and carries a contact element 45 in electrical connection therewith.

A cooperating resilient element 44 is controlled by the test lever 46 pivoted at 47 as shown. This test lever 46 is preferably made of insulating material. The resilient element 44 terminates at binding post 49, which serves for the connection of the device into the primary circuit, the other terminal being the binding post 50. The spark terminals of the secondary circuit 51 and 52 are connected respectively to the binding posts 53 and 54, as shown, which are intended to be connected to the terminals of the secondary winding of the transformer. In this form the spark terminals 51 and 52 are carried upon screw-threaded shanks 55 and 56, respectively, and are secured in adjusted position by means of the nuts 57. A hook 58 is provided upon resilient element 44 and to this a cord or other protective element 59 may be attached, corresponding to the cord or the like 14 of Fig. 2.

It will be understood, of course, that either the fuse 40 or the cord or equivalent device

59, may be employed, but that both would not ordinarily be used simultaneously, although it is possible that they could be simultaneously used if additional protection is sought, for example as shown in Fig. 3.

Either the cord 59 or the fuse wire 40 would be centered by the notches 43 of the lugs 41 and 42, so as to definitely position the protective element in proper position 10 with respect to the spark gap, to be destroyed upon the occurrence of a discharge.

Of course, a suitable protective casing may be provided for this form of device, if desired, or it might be placed within the box 15 containing the regular connections already provided in the circuit.

Having described my invention and several of the forms which it may take, I claim as my invention:

20 1. A protective device comprising a transformer feeding gas or vapor discharge devices, having a primary circuit and a secondary circuit, a destructible element maintaining the primary circuit of the transformer 25 in energized condition, and a spark gap connected in parallel to the secondary terminals of said transformer and open normally to such extent that sparks will not pass between the terminals, said destructible element located adjacent the terminals of the secondary 30 circuit whereby upon occurrence of an abnormal secondary potential a discharge will take place and destroy said element thereby interrupting the primary circuit of the transformer.

35 2. A protective device comprising a transformer feeding gas or vapor discharge devices, having a primary circuit and a secondary circuit, a fusible element maintaining the primary circuit of the transformer in energized condition, and a spark gap connected in parallel to the secondary terminals of said transformer and open normally to such extent that sparks will not pass between the terminals, said fusible element interposed 40 between the terminals of the secondary circuit whereby upon occurrence of an abnormal secondary potential a discharge will take place and destroy said element thereby interrupting the primary circuit of the transformer.

45 3. A protective device comprising a transformer feeding gas or vapor discharge devices having a primary circuit and a secondary 50 circuit a fusible conductor traversed by the primary current which maintains the primary circuit of the transformer in energized condition, and a spark gap connected in parallel to the secondary terminals of said 55 transformer and open normally to such extent that sparks will not pass between the terminals, said fusible conductor interposed between the terminals of the secondary circuit whereby upon occurrence of an abnormal 60 secondary potential a discharge will take 65

place and destroy said fusible conductor thereby interrupting the primary circuit of the transformer.

4. A circuit breaker of the class described, comprising: a secondary circuit; sparking points connected to opposite sides of said secondary circuit and in spaced relation to each other; a primary circuit; and a fusible strip of electric conducting material interposed in said primary circuit and positioned adjacent said sparking points.

In witness whereof I have hereunto set my hand at New York, county of Kings, New York, this 24th day of April, A. D. nineteen

hundred and twenty-nine.

WILLIAM M. BOUDION.
